UNITED STATES PATENT OFFICE.

ROY A. FRANCIS, OF BELLEVUE, KENTUCKY, ASSIGNOR TO THE CORCORAN-VICTOR COMPANY, OF CINCINNATI, OHIO, A CORPORATION OF OHIO.

DESIGN FOR A LAMP-DOOR.

51,481.

Specification for Design.

Patented Nov. 13, 1917.

Application filed July 30, 1917. Serial No. 183,630. Term of patent 14 years.

To all whom it may concern:

Be it known that I, Roy A. Francis, a citizen of the United States, and a resident of the city of Bellevue, in the county of Campbell and State of Kentucky, have invented a new, original, and ornamental Design for Lamp-Doors, of which the following is a specification, reference being had to the accompanying drawing, forming part thereof.

Figure 1 is a front elevation of the design.
Fig. 2 is a side elevation of the design.

I claim:

The ornamental design for a lamp door, as shown.

ROY A. FRANCIS.
